ELECTRIC STEAM IRON

Agatino Tricomi and Edward B. Tricomi,
Brooklyn, N. Y.

Application January 8, 1940, Serial No. 312,904

8 Claims. (Cl. 219—25)

This invention relates to new and useful improvements in an electric steam iron.

The invention particularly relates to an electric steam iron characterized by the provision of a flat sole base for contacting material being pressed and which has a steam generator located above and associated with control mechanism in a manner to cause steam to be generated and discharged for assisting said flat base in pressing the said material.

Still further it is proposed that the back of said iron be provided with a water container for supplying water to said steam generator connected thereto by means of a pipe system.

The invention has for an object the provision of a thermostatic controlled electric system for heating the iron and generator mounted on said generator in a manner to cause the same to be controlled by the passage of water through said pipe system to cause said system to be set into operation when more water is pumped to said generator and for causing said system to remain in operation a shorter period of time when less water is pumped to said generator.

Still further it is proposed that the thermostatic system be controlled by a bi-metal or other thermostatic switch mounted on said generator and having its control end disposed adjacent said pipe system to be closed thereby when cold water is pumped into the generator.

Still further it is proposed to provide a means for increasing or decreasing the space between said pipe system and said bi-metal or other thermostatic switch in a manner to control the degree of effectiveness of the pipe system upon said bi-metal switch.

A further object of this invention is the provision of a certain construction of a pump within said water container which is capable of pumping water from said container to said generator and further arranged in a manner to cause water to be sucked from a reservoir into said container to take the place of the water pumped therefrom into said generator.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an electric steam iron constructed in accordance with this invention.

Fig. 2 is a bottom plan view of Fig. 1.

Fig. 3 is a rear elevational view of Fig. 1.

Fig. 4 is a sectional view taken on the line 4—4 of Fig. 3.

Fig. 5 is a horizontal sectional view on the line 5—5 of Fig. 4.

Fig. 6 is a vertical sectional view on the line 6—6 of Fig. 4.

Fig. 7 is a vertical sectional view on the line 7—7 of Fig. 4.

Fig. 8 is a perspective view of the water container, per se.

Fig. 9 is a vertical sectional view on the line 9—9 of Fig. 4.

Fig. 10 is a vertical sectional view on the line 10—10 of Fig. 4.

Fig. 11 is an enlarged detailed view of a portion of Fig. 10.

Fig. 12 is a partial plan view on the line 12—12 of Fig. 6.

Fig. 13 is a schematic wiring diagram of the device.

Fig. 14 is an enlarged sectional view of the electric heater, per se.

Fig. 15 is a view similar to Fig. 6 illustrating a modification of the invention.

Fig. 16 is a perspective view of the eccentric washer per se.

The electric steam iron, according to this invention, includes a flat sole base 10 having an internal passage 11 with an inlet on the top of the base and a plurality of pin hole exhausts 12 on the bottom of the base. This flat sole base is constructed of metal and of separate layers 10^a and 10^b. Each of the sections 10^a and 10^b have a portion of the passage 11 ground therein and aligned with each other in a manner to form a circular passage when the section 10^a is superimposed on the section 10^b. The inlet extends through the top section 10^a of the pin hole exhausts and extends through the bottom section 10^b. After the sections have been provided with the internal passage 11 they are adapted to be fabricated together to form a single unit.

A flat electric heater 13 is mounted on the top of the flat base 10 and has a heavy central insulation member 13^a upon which the incandescent winding 13^b is positioned. This incandescent winding is so arranged that a portion thereof extends across the top face of the heavy central insulation 13^a, and a portion thereof extends across the bottom of the heavy central insulation 13^a. The portion of the winding which is extended across the bottom of the insulation 13^a is adapted to heat the flat sole base 10. A

steam generator 14 is superimposed upon the flat electric heater 13 and is provided with a hollow chamber 14^a within which the steam is adapted to be generated. A thin insulation member 13^c is mounted upon the top portion of the winding 13^b and is disposed between the winding and the bottom face of the generator 14 for insulating the generator from the winding. Likewise, an insulation member 13^b is positioned upon the bottom of the winding 13^b and is disposed between the sole plate and the winding 13^b. These insulation members 13^c and 13^d are sufficiently thin to permit the heat to pass to the generator and to the sole plate individually of each other. However, these two insulation members 13^c and 13^d, in conjunction with the insulation member 13^a, act to insulate the sole base 10 from the generator 14 to prevent the ready conduction of heat from the sole base 10 to the generator 14, and vice versa.

A hollow cover 15 is extended over the heater 13 and the generator 14 and is maintained in position with relation to the generator by means of a screw 16. The screw 16 passes through an opening in the top of the cover 15 and threadedly engages into the generator 14. Likewise, a means is provided for retaining the generator and the electric heater 13 in position upon the flat sole base. This means comprises a pair of screws 17 freely extended through the generator 14 and the heater 13 and threadedly engaged into the top section 10^a of the sole base 10. A handle 18 is mounted on the cover 15 and provides a means by which the iron may be conveniently manipulated while being used to press material over which it is being passed.

A hollow water storage container 19 is fixedly mounted on the back of the handle 18. This water container 19 has a pipe 20 extending therefrom to a reservoir for conveying water from said reservoir to said container. A water pump is located within the storage container 19 and is arranged in a particular manner to pump water from the storage container to the generator and for drawing water from the reservoir to the water container to displace the water pumped from the container to the generator. This pump comprises a cylinder 22 mounted upon the front wall of the water container 19 which has a piston 23 slidably mounted therein. This piston 23 is provided on its bottom face with a fabric sealing means 24 which is adapted to seal that portion of the container located above the piston from that portion of the container located below the piston. The top portion of the cylinder 22 is connected to the interior of the water container 19 by means of a pin hole passage 25 located in the top wall of the cylinder 22. A spring 26 is arranged in the bottom portion of the container and operates between the bottom wall thereof and the bottom face of the fabric member 24 for urging the piston 23 into its up position.

A means is provided for causing the piston 23 to be reciprocated within the container 22. This means includes a piston rod 27 which extends through the top wall of the cylinder 22. An operator rod 28 extends through the handle 18 and has one of its ends passing into the interior of the container 19. At the point where the operator rod 28 passes into the container 19 a packing gland 29 is provided for sealing the opening through which the operator rod extends. A link system 30 is extended between the inner end of the operator rod 28 and the top end of the piston rod 27 for causing the piston rod 27 to move

downwards when the operator rod 28 is pivoted. The front end of the operator rod is extended from the front end of the handle 18 and is provided with a thumb plate 31 by which the rod 28 may be conveniently pivoted for causing the rod 27 to move downwards.

A means is also provided for controlling the stroke of the piston 23 and also the distance through which the operator rod 28 may be pivoted. This means includes a shaft 32 extending downwards from the bottom face of the piston 23 and coaxially through the spring 26. This shaft 36 also acts to centrally locate the spring 26 and prevent the same from buckling under the compression of the piston 23. The bottom end of the shaft 32 extends into an extension 22^a threadedly mounted on the bottom wall of the cylinder 22. This extension 22^a has a control handle 33 extended through the bottom wall of the water container 19 and which is provided with a knob 34 by which it may be conveniently turned for controlling the distance between the bottom end of the shaft 32 and the bottom wall of the extension 22^a to control the distance through which the piston may be moved before the bottom end of the shaft strikes the bottom end of the extension. This control handle 33 is slidably extended through the opening in the bottom wall of the container 19, but is sufficiently tight to prevent the leakage of water.

An inlet pipe 35 is connected with the interior of the cylinder 22 and has its other end disposed adjacent the back wall of the container 19. A valve 36 is mounted within the inlet pipe 35 and is arranged to permit a free passage of water into the cylinder on the up stroke of the piston but to prevent the passage of water therethrough on the down stroke of the piston. A pipe system 37 is provided for conveying the water from the pump to the generator 14. This means comprises a section of pipe 37^a extending from the pump to the exterior of the water container 19. It also comprises a section of pipe 37^b connected to the hollow 14^a of the generator 14 and which extends through an opening formed in the back of the cover 15. These pipe sections 37^a and 37^b are connected together at a point between the back face of the cover 15 and the front face of the water container 19 by means of a union 38. The section of pipe 37^a is provided with a valve 39 arranged to permit the free passage of water on the down stroke of the piston 23 but prevent the passage of water on the up stroke of the piston 23. The normal water line of the container 19 is indicated at 40 in Fig. 4.

The operation of this pump is as follows:

When the thumb plate 31 is depressed to pivot the operator rod 28 the piston 23 will move downwards within the cylinder 22 and force any water located within the bottom portion of the pump through the pipe system 37 into the hollow 14^a of the generator 14. This downward movement of the piston 23 causes the one way valve 36 to close and the one way valve 39 to open to direct the water from the pump to the generator 14. When the operator rod 28 is released the spring 26 contained within the cylinder 22 will urge the piston 23 upwards to cause the one way valve 39 to be closed and to open the one way valve 36 to cause a quantity of water to be withdrawn from the water container 19 into the cylinder of the pump for the next down stroke thereof. Similarly, this pump is arranged to draw a quantity of water from the reservoir to displace the water pumped into the generator.

This is caused upon the down stroke of the piston 23 which causes a vacuum in the top portion of the piston 22 which will cause the air located within the water container 19 above the water

5 line 40 to pass into the pump to fill the vacuum created by the down stroke of the piston.

This passage of air from the water container to the piston creates a vacuum within the water container 19 to cause water to be sucked from 10 the reservoir through the pipe 21 into the container 19. When the piston 23 moves upwards the air contained within the top portion of the cylinder 22 will pass out through the pin hole passage 25 and into the interior of the water container 19. On each movement of the operator rod 28 the pump acts as described to pump a quantity of water from the container 19 to the generator and to suck a quantity of water from the reservoir to the water container.

20 A thermostatic electric system sensitive to the temperature of the pipe system 37 is mounted upon the steam generator for controlling the operation of the electric heater 13. An electric cord 42 extends into the back of the handle 18 and is provided at its free end with a conventional plug 43 adapted to be engaged into a conventional house outlet. The two ends of the electric cord 42 are attached to metallic clips 44 mounted in position upon the back portion 25 of the handle 18 by means of screws 45. The thermostatic electric system is characterized by a bi-metal electric switch mounted on a portion of the generator 14. This switch is characterized by a straight piece of non-sensitive metal 35 45 carrying an electrical contact 46 at its free end. Similarly, a second piece of sensitive metal 47 is disposed beneath the piece of metal 45 and has its end bent to engage over the end of the piece of metal 45. The free end of the sensitive 40 piece of metal 47 carries a contact 48 which is adapted to engage the contact 46 to complete a circuit 49 which also includes the incandescent winding 13^b of the electric heater 13. These pieces of metal 45 and 47 are spaced from each 45 other by means of an insulation member 50, and are in turn mounted upon a piece of insulation member 50 mounted upon the generator 14.

This bi-metal switch is so mounted upon the generator that the operative bent end of the 50 sensitive piece of metal 47 is disposed immediately adjacent the section of pipe 37^b to be influenced thereby as cool water passes therethrough. When cool water is pumped through the section of pipe 37 it will tend to cool the atmosphere therearound and bend the end of the sensitive piece of metal 47 to cause the contacts 46 and 48 to engage each other. Likewise, as the temperature of the surrounding temperature rises when water is not being pumped 55 through the section of pipe 37^b it will cause the sensitive piece of metal 47 to be bent to a position in which the contacts 46 and 48 will be disengaged from each other. The non-sensitive piece of metal 45 has a member 51 attached thereto and which is provided with a prong 52 which extends upwards into an opening formed in the handle 18 to contact one of the screws 45. The sensitive piece of metal 47 is connected by means of a connecting member 53 to one end of the incandescent winding 13^b of the electric heater 13. The other end of the incandescent winding 13^b is provided with a metallic member 54 provided with an upwardly extending prong 55. This prong 55 extends upwards into another opening formed in the han-

dle 18 to contact the other screw 45 and complete the circuit 49 from the plug 43 through the contacts 46, 48 and the incandescent winding 13^b.

A means is provided for controlling the sensitivity of the bi-metal switch and includes a bracket 56 mounted above the nonsensitive piece of metal 45 and insulated therefrom by means of an insulation member 57. A screw 58 is threadedly engaged through the free end of the 10 bracket 56 and has its bottom end bearing against an insulation member 59 mounted upon the top face of the nonsensitive piece of metal 45. This screw 58 extends through an opening formed in the top face of the cover 15 and is 15 provided with a handle 59 by which it may be conveniently rotated to change its relative position with relation to the bracket 16 and cause a greater or lesser amount to be extended from the bottom face thereof. This movement of the 20 screw 58 also causes the nonsensitive piece of metal 45 to be flexed to control the distance between the contacts 46 and 48 to vary the temperature required for causing the contacts to 25 engage each other and for causing the contacts to disengage each other. Thus the bi-metal switch may be adjusted to cause the iron to be heated to a greater degree for pressing material such as cotton, wool, etc., and to be heated to a lesser degree for pressing silks and acetates. 30 The knob 59 is provided with a pointer 59^a acting across a scale 60 formed on the top of the cover to indicate the adjustment of the screw for low, medium or high heat.

The operation of the heating unit is as follows:

The heating unit is automatically controlled by means of a thermostatic switch for various materials inasmuch as the unit will heat to a high non-scorch heat for all fabrics. Various 40 degrees of heat may be obtained from the unit to steam and press materials of various consistencies. For example, in pressing acetates steam is needed, but not in such great quantity, and a low heat is also required. This may be 45 obtained by merely pressing the material with the right amount of steam which will cause the iron to maintain the right temperature. In pressing cotton, which requires a high degree of heat, it normally follows that a higher degree 50 of heat also demands a higher quantity of moisture and therefore by using a greater quantity of steam the unit will automatically increase its heat. This automatic operation is due to the fact that materials requiring a larger quantity 55 of steam or moisture to cause the same to be pressed, naturally require a higher amount of heat to press or bake the nap consistency of the material. The same is true for materials requiring a lesser amount of steam which naturally 60 require a lesser amount of heat.

Bearing this in mind, it is noted that as the heat is controlled by the amount of steam actually needed by the material, the use of the proper amount of steam on the material automatically 65 adjusts the proper amount of heat developed for the material by the heating unit by means of the thermostatic bi-metal switch which is located on top of the steam generator with its operative end located near the inlet water pipe section 37^b. If 70 water enters through this pipe 37^b, which is at the time hot, it naturally becomes cool, causing the tip end of the bottom of the switch to react from the air cooled by the water that is expelled from the pump through which the water entered the 75

steam generator. Said reaction by the metallic switch causes the contacts 46 and 48 to be engaged, thus allowing the heating unit to heat the sole base 10 and also supply heat to the steam generator 14 to transform the water that has entered into steam. As we continue to pump water through the pipe section 37^b into the generator 14 the cooling effects thereof prolong the duration of engagement of the contacts 46 and 48, causing more heat to be developed to heat the unit to a higher degree, useful in pressing cottons, etc.

The continued pumping of water to the generator permits the iron to heat to a high non-scorch temperature and the heat radiated from the steam generator 14 will cause the operative end of the thermostatic bi-metal switch to be flexed and cause the contacts 46 and 48 to be disengaged when the heat thereof reaches a sufficiently high temperature to affect the operation of the switch.

When the pump is actuated by movement of the control stem 38 water will enter through the pipe section 37^b and cool the generator 14, but not sufficiently enough to cause the thermostat to make contact, but on the second stroke when the pipe 37^b becomes sufficiently cold to cause the bent end of the sensitive metal plate 47 to bend and temporarily make contact. In the meantime the generator cooling proportionately will cause the thermostat switch to react normally and hold the said contact if more water is being allowed to enter the generator at this time. If no more water is allowed to enter the generator it will heat up again to a high non-scorch heat temperature and break the contact. While the steam generator had a high non-scorch steam temperature the same condition prevailed in the flat sole base 10. When the water entered the generator the sole base temperature was not increased nor cooled thereby, but when the second water entered the generator and the thermostat made contact indicating the fact that material being pressed needed more steam, it naturally also needed more heat.

The fact is, that regardless of the amount of steam being generated it will absorb a percentage of the heat from the sole base 10, naturally keeping the temperature of the sole base 10 at the same level. This condition is made possible by using insulation members between the sole base 10 and the steam generator 14 and upon which the incandescent winding 13^b is mounted. Thus as the steam generator cools the insulation members between the generator and sole base 55 prevents the cooling of the generator from acting upon the sole base, thus creating two independent temperatures, one for the sole base and one for the generator. The reason for the two temperatures is that the generator may cool and heat rapidly without affecting the temperature of the sole base, although the sole base is subject to a rising temperature, but this condition is taken care of by the absorption of heat from the sole base by the material being pressed.

According to the modification of the invention shown in Figs. 15 and 16 the construction of the electric steam iron is similar to that previously described, except for the provision of a means for controlling the space between the pipe section 70^b and the operative end of the thermostatic bi-metal switch. This means comprises an eccentric bushing 50 mounted upon the pipe section 37^b and held in various turned positions thereon by means of a set screw 51'. This bushing may be turned to various positions upon the pipe section

37^b for controlling the space between the pipe section and the operative end bi-metal switch for controlling the radiation of the cool atmosphere from the pipe section 37^b to the bi-metal switch. In other respects this form of the invention is similar to the previous form and like parts may be identified by like reference numerals.

While we have illustrated and described the preferred embodiments of our invention, it is to be understood that we do not limit ourselves to the precise constructions herein disclosed and the right is reserved to all changes and modifications coming within the scope of the invention as defined in the appended claims.

Having thus described our invention, what we claim as new, and desire to secure by United States Letters Patent is:

1. In an electric steam iron, a flat sole base having an internal passage with an inlet on the top of the base and a plurality of pin hole exhausts upon the bottom of the base, a flat electric heater mounted on the top of said flat base and having a heavy central heat insulation member with sections of the incandescent winding on the top and bottom thereof, a steam generator mounted on the top of said heater, a hollow cover mounted on the top of said base for encasing said heater and steam generator, a handle on said cover, a water storage container mounted on the rear of said handle, a water pump in said container and having a rod extending through said handle and at its outer end having a finger operable handle and a pipe system connecting the exhaust of said pump with the steam generator, and a thermostatic electric system sensitive to the temperature of said pipe system of said steam generator for controlling said electric heater.

2. In an electric steam iron, a flat sole base having an internal passage with an inlet on the top of the base and a plurality of pin hole exhausts upon the bottom of the base, a flat electric heater mounted on the top of said flat base and having a heavy central heat insulation member with sections of the incandescent winding on the top and bottom thereof, a steam generator mounted on the top of said heater, a hollow cover mounted on the top of said base for encasing said heater and steam generator, a handle on said cover, a water storage container mounted on the rear of said handle, a water pump in said container and having a rod extending through said handle and at its outer end having a finger operable handle and a pipe system connecting the exhaust of said pump with the steam generator, and a thermostatic electric system sensitive to the temperature of said pipe system of said steam generator for controlling said electric heater, said thermostatic electric system including a thermostatic bi-metal switch mounted upon said generator and having its operative end disposed adjacent said pipe system to be influenced by the temperature of the water passing therethrough.

3. In an electric steam iron, a flat sole base having an internal passage with an inlet on the top of the base and a plurality of pin hole exhausts upon the bottom of the base, a flat electric heater mounted on the top of said flat base and having a heavy central heat insulation member with sections of the incandescent winding on the top and bottom thereof, a steam generator mounted on the top of said heater, a hollow cover mounted on the top of said base for encasing said heater and steam generator,

- a handle on said cover, a water storage container mounted on the rear of said handle, a water pump in said container and having a rod extending through said handle and at its outer 5 end having a finger operable handle and a pipe system connecting the exhaust of said pump with the steam generator, and a thermostatic electric system sensitive to the temperature of said pipe system of said steam generator for 10 controlling said electric heater, said thermostatic electric system including a thermostatic bi-metal switch mounted upon said generator and having its operative end disposed adjacent said pipe system to be influenced by the temperature of 15 the water passing therethrough, said switch being characterized by a stiff metallic member and a sensitive metallic member, contacts mounted on the ends of said members, said sensitive metallic member being arranged to flex to cause 20 said contacts to engage each other when the temperature of the surrounding atmosphere goes down, and to disengage said contacts when the temperature of said atmosphere goes up.
4. In an electric steam iron, a flat sole base 25 having an internal passage with an inlet on the top of the base and a plurality of pin hole exhausts upon the bottom of the base, a flat electric heater mounted on the top of said flat base and having a heavy central heat insulation 30 member with sections of the incandescent winding on the top and bottom thereof, a steam generator mounted on the top of said heater, a hollow cover mounted on the top of said base for 35 encasing said heater and steam generator, a handle on said cover, a water storage container mounted on the rear of said handle, a water pump in said container and having a rod extending through said handle and at its outer 40 end having a finger operable handle and a pipe system connecting the exhaust of said pump with the steam generator, and a thermostatic electric system sensitive to the temperature of 45 said pipe system of said steam generator for controlling said electric heater, said thermostatic electric system including a thermostatic bi-metal switch mounted upon said generator and having its operative end disposed adjacent said pipe system to be influenced by the temperature of 50 the water passing therethrough, and a means for controlling the temperature at which said thermostatic switch will operate, said water pump being disposed within said water storage container and arranged to pump water from said water container to said generator and to simultaneously suck a quantity of water from a reservoir to said water container to displace the water pumped to said generator.
5. In an electric steam iron, a flat sole base 55 having an internal passage with an inlet on the top of the base and a plurality of pin hole exhausts upon the bottom of the base, a flat electric heater mounted on the top of said flat base and having a heavy central heat insulation member with sections of the incandescent winding on the top and bottom thereof, a steam generator mounted on the top of said heater, a hollow cover mounted on the top of said base for 60 encasing said heater and steam generator, a handle on said cover, a water storage container mounted on the rear of said handle, a water pump in said container and having a rod extending through said handle and at its outer 65 end having a finger operable handle and a pipe system connecting the exhaust of said pump with the steam generator, and a thermostatic electric system sensitive to the temperature of 70 said pipe system of said steam generator for controlling said electric heater, said thermostatic electric system including a thermostatic bi-metal switch mounted upon said generator and having its operative end disposed adjacent said pipe system to be influenced by the temperature of 75 the water passing therethrough, and a means for controlling the temperature at which said thermostatic switch will operate, said water pump being disposed within said water storage container and arranged to pump water from said water container to said generator and to simultaneously suck a quantity of water from a

to be influenced by the temperature of the water passing therethrough, and a means for controlling the temperature at which said thermostatic switch will operate, said means comprising an adjustment screw engaging said switch for increasing the space between the contacts thereof for varying the distance through which said sensitive element must flex before said contacts will engage each other.

6. In an electric steam iron, a flat sole base 10 having an internal passage with an inlet on the top of the base and a plurality of pin hole exhausts upon the bottom of the base, a flat electric heater mounted on the top of said flat base and having a heavy central heat insulation 15 member with sections of the incandescent winding on the top and bottom thereof, a steam generator mounted on the top of said heater, a hollow cover mounted on the top of said base for 20 encasing said heater and steam generator, a handle on said cover, a water storage container mounted on the rear of said handle, a water pump in said container and having a rod extending through said handle and at its outer 25 end having a finger operable handle and a pipe system connecting the exhaust of said pump with the steam generator, and a thermostatic electric system sensitive to the temperature of 30 said pipe system of said steam generator for controlling said electric heater, said thermostatic electric system including a thermostatic bi-metal switch mounted upon said generator and having its operative end disposed adjacent said pipe system to be influenced by the temperature of 35 the water passing therethrough, and a means for controlling the temperature at which said thermostatic switch will operate, said water pump being disposed within said water storage container and arranged to pump water from said water container to said generator and to simultaneously suck a quantity of water from a reservoir to said water container to displace the water pumped to said generator.

7. In an electric steam iron, a flat sole base 45 having an internal passage with an inlet on the top of the base and a plurality of pin hole exhausts upon the bottom of the base, a flat electric heater mounted on the top of said flat base and having a heavy central heat insulation 50 member with sections of the incandescent winding on the top and bottom thereof, a steam generator mounted on the top of said heater, a hollow cover mounted on the top of said base for 55 encasing said heater and steam generator, a handle on said cover, a water storage container mounted on the rear of said handle, a water pump in said container and having a rod extending through said handle and at its outer 60 end having a finger operable handle and a pipe system connecting the exhaust of said pump with the steam generator, and a thermostatic electric system sensitive to the temperature of 65 said pipe system of said steam generator for controlling said electric heater, said thermostatic electric system including a thermostatic bi-metal switch mounted upon said generator and having its operative end disposed adjacent said pipe system to be influenced by the temperature of 70 the water passing therethrough, and a means for controlling the temperature at which said thermostatic switch will operate, said water pump being disposed within said water storage container and arranged to pump water from said water container to said generator and to simultaneously suck a quantity of water from a

reservoir to said water container to displace the water pumped to said generator, said pump having a piston dividing the interior thereof into a bottom portion for causing water to be pumped 5 from said container to said generator and a top portion for causing the water to be sucked from said reservoir to said container on one downward movement of said piston.

8. In an electric steam iron, a flat sole base 10 having an internal passage with an inlet on the top of the base and a plurality of pin hole exhausts upon the bottom of the base, a flat electric heater mounted on the top of said flat base and having a heavy central heat insulation 15 member with sections of the incandescent winding on the top and bottom thereof, a steam generator mounted on the top of said heater, a hollow cover mounted on the top of said base

for encasing said heater and steam generator, a handle on said cover, a water storage container mounted on the rear of said handle, a water pump in said container and having a rod extending through said handle and at its outer 5 end having a finger operable handle and a pipe system connecting the exhaust of said pump with the steam generator, and a thermostatic electric system sensitive to the temperature of said pipe system of said steam generator for 10 controlling said electric heater, and means for controlling the operative distance between said pipe system and said thermostatic electric system controlling the radiation of heat between these parts to influence the operation of said thermostatic system. 15
